US00D542423S

(12) United States Design Patent (10) Patent No.: US D542,423 S
Baur et al. (45) Date of Patent: * May 8, 2007

(54) RAIL BALUSTER

(75) Inventors: Gerhard Baur, Lefaivre (CA);
Wolfgang Johannes Baur, Alfred (CA)

(73) Assignee: Wolf's Archtec.Iron Designs Inc. (CA)

() Term: 14 Years

(21) Appl. No.: 29/229,431

(22) Filed: May 6, 2005

(30) Foreign Application Priority Data

Apr. 20, 2005 (CA) 110776

(51) LOC (8) Cl. 25-01

(52) U.S. Cl. D25/126; D25/38

(58) Field of Classification Search 256/73,
256/1, 59, 67, 65.02, 65.11, 65.15, 65.16,
256/19, 21, 22, 24, 25; D25/38, 42, 44, 50;
52/720.2

See application file for complete search history.

(56) References Cited

U.S. PATENT DOCUMENTS

3,092,372 A * 6/1963 Cougle 256/22
D237,408 S * 10/1975 Larson D25/132
4,386,761 A * 6/1983 Kato 256/21
D399,980 S * 10/1998 Masse D25/126
5,820,111 A * 10/1998 Ross 256/65.11
6,059,269 A 5/2000 Ross 256/65
D451,205 S * 11/2001 Erwin D25/38
2002/0070377 A1 * 6/2002 Erwin 256/1

FOREIGN PATENT DOCUMENTS

CA 87302 8/1999

1 Claim, 1 Drawing Sheet

CA 1020614 5/2004

CA 1020615 5/2004
OTHER PUBLICATIONS

Catalogue by Prestige Metal, 23 pages, published Jan. 1991.
Catalogue by Prestige Metal entitled B-Series Balusters, 1 page, published Jan. 1991.

Designs of Regency Railings Tuscany and Tuscany with verticals, 2 pages, subject of U.S. Patents 5,820,111 and 6,059,259.

Catalogue by Euro-Fer (an Italian company) for designs entitled Martellato/Hammered (Art.05.542) and Liscio/Smooth (Art.05.532), Modell Scala Scala Model (Art.04.048.01), 3 pages, published Jan. 2004.

Catalogue by Glasser (a German company), 3 pages, published 1986.

“Tafel 24,” from a German Metal Welders book (title unknown), 1 page, published 1897.

* cited by examiner

Primary Examiner—Doris Clark

(74) Attorney, Agent, or Firm—Ostrolenk, Faber, Gerb & Soffen, LLP

(57) CLAIM

The ornamental design for a rail baluster, as shown and described.

DESCRIPTION

The FIGURE is a front view of a rail baluster showing my new design.

The Figure